Filed Jan. 31, 1967, Ser. No. 5,635

Term of patent 14 years

(Cl. D26—14)

FIGURE 1 is a perspective view of a case for a wrist watch communication receiver showing our new design;

FIGURE 2 is a top plan view thereof;

FIGURE 3 is a bottom plan view thereof;

FIGURE 4 is a side elevational view thereof as seen from one side;

FIGURE 5 is a side elevational view thereof as seen from the other side;

FIGURE 6 is an end elevational view as seen from one end thereof; and

FIGURE 7 is an end elevational view as seen from the other end thereof.

The broken line showing of a wrist strap in FIGURE 1 is merely for illustrative purposes.

We claim:

The ornamental design for a case for a wrist watch communication receiver, substantially as shown and described.
